US00D971360S

(12) **United States Design Patent** (10) **Patent No.:** **US D971,360 S**
Ye et al. (45) **Date of Patent:** **** Nov. 29, 2022**

(54) **HOVERBOARD**
(71) Applicant: **ZHEJIANG TAOTAO VEHICLES CO., LTD.**, Lishui (CN)
(72) Inventors: **Hang Ye**, Lishui (CN); **Hongxia Zhu**, Lishui (CN)
(73) Assignee: **ZHEJIANG TAOTAO VEHICLES CO., LTD.**, Lishui (CN)
(**) Term: **15 Years**
(21) Appl. No.: **29/788,992**
(22) Filed: **Aug. 24, 2021**

(57) **CLAIM**

The ornamental design for a hoverboard, as shown and described.

DESCRIPTION

FIG. 1 is a front perspective view of a hoverboard showing our new design;

FIG. 2 is a top perspective view thereof;

FIG. 3 is a front view thereof;

FIG. 4 is a rear view thereof;

FIG. 5 is a left side view thereof, the right side view being identical;

FIG. 6 is a top view thereof; and,

FIG. 7 is a bottom view thereof.

The broken lines in the figures illustrate portions of the hoverboard that form no part of the claimed design.

1 Claim, 7 Drawing Sheets
